CLAIM

The ornamental design for a dispenser for a skin care composition, as shown and described.

DESCRIPTION

FIG. 1 is a perspective view of a dispenser for a skin care composition;

FIG. 2 is a front elevation view thereof;

FIG. 3 is a left elevation view thereof;

FIG. 4 is a back elevation view thereof;

FIG. 5 is a right elevation view thereof;

FIG. 6 is a top plan view thereof; and,

FIG. 7 is a bottom plan view thereof.

The broken lines depict the portions of the dispenser for a skin care composition that form no part of the claimed design.

1 Claim, 3 Drawing Sheets
